UNITED STATES PATENT OFFICE.

CHARLES J. REYNOLDS AND OLIVER E. CHAPMAN, OF BOSTON, MASSACHUSETTS, ASSIGNORS TO UNIVERSAL CAR SEAL COMPANY, OF KITTERY, MAINE, AND BOSTON, MASSACHUSETTS, A CORPORATION OF MAINE.

SEAL FOR SEAL-LOCKS.

SPECIFICATION forming part of Letters Patent No. 744,235, dated November 17, 1903.

Application filed June 13, 1902. Serial No. 111,500. (No model.)

To all whom it may concern:

Be it known that we, CHARLES J. REYNOLDS and OLIVER E. CHAPMAN, citizens of the United States, residing in Boston, in the 5 county of Suffolk and State of Massachusetts, have invented a new and useful Improvement in Seals for Seal-Locks, of which the following is a specification.

This invention relates to seals (preferably 10 metallic) which are adapted to extend into or between plates or locking devices making portions of seal-locks, such as are particularly applicable to freight-cars, although such seal-locks are sometimes used in other connections. The seal usually consists of a narrow 15 flexible strip of metal having stamped upon it letters or characters referring to the railroad, destination of the freight-car, &c.

Our improved seal is intended particularly 20 for application to seal-locking contrivances in which the seal extends from the lock through a slotted pin, to which it is to be secured in such a manner that it cannot be withdrawn or removed without exhibiting indications of its 25 having been tampered with.

In the accompanying drawings, in which similar letters of reference indicate corresponding parts, Figure 1 is an elevation of our improved seal. Fig. 2 is a similar view 30 with the location of the lock when the seal is in the position indicated in dotted lines. Fig. 3 is an enlarged section taken on line X, Fig. 1. Fig. 4 is a front view of a portion of the side of a freight-car, showing the manner in 35 which the seal is used.

a represents the narrow flexible metallic strip provided with openings *b*, through which the bolt or bolts of a suitable lock *s* are intended to extend when the seal is in position 40 in the lock. The strip portion is adapted to receive suitable letters or characters applied in the ordinary manner. At one end this strip *a* is provided with wings *c*, whereby a broadened end or head *d* is produced, said 45 head being provided also with embossed or raised letters or characters *e*, whereby such broadened end is rendered practically thicker than the main or strip portion *a*, the thickness thus produced being greater than the 50 ordinary width of the slot in the pin into

which the seal is to be thrust. The wings *c* broaden the head *d* of the seal enough to make it broader than the length of said slot. The letters or characters on the head *d* may indicate the owner or manufacturer of the 55 seal or be of the nature of advertising. They are not, however, usually intended to indicate the destination of the car, as such letters are usually placed upon the strip portion *a* of the seal. At *g* the head is scored 60 or grooved in line with the opposite edges of the strip *a*, said scores extending for an appreciable distance below the surface of the head and across it. A tongue *h* is formed longitudinally in the seal by means of the 65 **U**-shaped cut *k*, said tongue extending from the main portion of the seal through the neck or part which extends through the slot in the pin and into the head, preferably intersecting the embossed letters therein. At a 70 point in the seal a little to the rear of the lock when it is in position is a hole *l* of any desired shape.

In Fig. 4 a seal-lock *s* of any suitable construction having internal projections which 75 are adapted to extend through the slots *b* is suspended by a chain *m* from the side *n* of a freight-car. A pin *q*, suitably slotted vertically, as indicated at *w*, Fig. 2, is suspended 80 by a chain *r* from the car and hangs through a staple *t*, driven into said car. A slotted hasp *u* swings from the door *v* of the car and rests on and around the staple between the pin *q* and the side of the car.

In practice the rear end of the main portion 85 *a* of the seal is thrust through the slotted pin *q* and into the lock *s*, where it is held by suitable projections in the ordinary manner. As the head *b* is broadened by means of the wings *c* until it is wider than the slot *w* in the pin *q*, 90 (see Fig. 2,) it cannot while retaining its shape be drawn through said slot. Should a person endeavor to tamper with the seal and draw the head through the slot by folding it inward, so as to make it of the same width as the strip portion *a*, he would naturally and practically necessarily make the folds at the scores *g*. If the seal were not broken when the wings *c* were folded in, it would become 95 broken at the scores when the wings were 100

- folded back, and thus show that the seal had been tampered with. The embossed characters *e* thicken the head *d*, so that its thickness is greater than the width of the slot in the pin, and thus provide another means of detecting an attempt to tamper with the seal, inasmuch as the embossing must be hammered down in order to pull the seal through the slot.
- The hole *l*, which is formed close to the rear end of the lock when the latter is in position, so as to be visible outside the lock, is intended to indicate any tampering with the seal, which would change the relative position of the lock and seal.
- 15 The tongue *h*, which extends from the main portion *a* just inside the lock into the head *d*, its free end being in said head, is necessarily crossed by the pin when the seal is in position in the lock, as illustrated in Fig. 2.
- 20 Should a person cut the seal either legitimately or illegitimately between the head thereof and the lock in order to cut off the head, he must sever it either between the pin and the seal or between the pin and the head.
- 25 In either case the tongue is severed and its end falls out, leaving a hole in the head, and thereby preventing the head, tongue, and strip portion *a* from being united by soldering or otherwise returned to their original position without detection. Hence legitimate cutting, which must be across the tongue, severs the tongue, so that the seal cannot be used again.
- No claim is made in this application on the lock or on any of the parts *m*, *q*, *r*, *t*, and *u*, as this invention relates solely to the seal, and said seal may be used in connection with any lock provided with projections adapted to extend through holes in the seal and with any

pin or similar device formed with a slot of suitable width and length to admit the body of the seal, but not to allow the passage through it of the head thereof.

Having thus fully described our invention, what we claim, and desire to secure by Letters Patent, is—

1. A seal for seal-locks, consisting of a strip *a* adapted to be secured to the lock, and a head *d* provided with one or more laterally-extending wings *c*, said head being formed with one or more grooves or scores *g* in line with the edges of the strip, for the purpose set forth.

2. A seal for seal-locks, consisting of the strip *a*, and a head adapted to be held by a suitably-slotted pin, said head and strip being provided with a tongue *h* extending across the point at which the pin embraces or crosses the seal, said tongue having one end free to drop from the seal in case the tongue is severed, for the purpose set forth.

3. A seal for seal-locks, consisting of a strip *a* provided with one or more slots *b* adapted to be engaged by and within the seal-lock when the strip is in position, and a head integral with and broader than said strip, the said strip being provided with a hole *l* additional to the slots *b* and located at a point outside the lock when the seal is in position therein, for the purpose set forth.

In testimony whereof we have signed our names to this specification in the presence of two subscribing witnesses.

CHARLES J. REYNOLDS.
OLIVER E. CHAPMAN.
